CLAIM

The ornamental design for a nasal dilator, as shown and described.

DESCRIPTION

FIG. 1 is a perspective view of a nasal dilator showing our new design;

FIG. 2 is an enlarged view of the left side of the nasal dilator shown in FIG. 1 taken along line 2;

FIG. 3 is a front view of the nasal dilator shown in FIG. 1; FIG. 4 is an enlarged view of the left side of the nasal dilator shown in FIG. 3 taken along line 4;

FIG. 5 is a back view of the nasal dilator shown in FIG. 1; FIG. 6 is an enlarged view of the left side of the nasal dilator shown in FIG. 5 taken along line 6;

FIG. 7 is a top view of the nasal dilator shown in FIG. 1; FIG. 8 is an enlarged view of the left side of the nasal dilator shown in FIG. 7 taken along line 8;

FIG. 9 is an end view of the right side of the nasal dilator shown in FIG. 1;

FIG. 10 is an enlarged view of FIG. 9;

FIG. 11 is an end view of the left side of the nasal dilator shown in FIG. 1; and,

FIG. 12 is an enlarged view of FIG. 11.

In the drawings the broken lines represent features of the nasal dilator that form no part of the claimed design.
